IMMERSION ACTUATOR

Harry C. Grant, Jr., New York, N. Y., assignor to
Specialties Development Corporation, Bloom-
field, N. J., a corporation of New Jersey

Application May 14, 1941, Serial No. 393,401

11. Claims. (Cl. 200—152).

The present invention relates broadly to actuators for use with automatically operable marine life saving apparatus such as, for example, aircraft flotation equipment, now extensively used to prevent the sinking of aeroplanes not otherwise equipped to float when forced to descend upon a body of water.

More specifically, this invention relates to an actuator which, upon immersion in water, completes an electric actuating circuit to operate electrically releasable aircraft flotation equipment, as suggested, for instance, in United States Letters Patent Serial No. 1,956,494, issued to Dagnall.

An object of the present invention is to provide an actuator of the type referred to, which is simple in construction, economical to manufacture, and efficient and reliable in operation.

Another object is to provide an electric circuit actuator which is easily mounted and dismounted.

Another object is to provide an actuator which permits of easy access to the inside thereof for purposes of test and inspection.

A further object is to provide an immersion actuator the construction of which impedes an undesired operation thereof.

These, and other objects of the invention not specifically enumerated above, will be apparent as the invention is described in greater detail in connection with the accompanying drawings, wherein:

Figure 1 is a schematic view of an electrical circuit, shown in part, incorporating an immersion actuator in accordance with the invention.

Figure 2 is a partial longitudinal cross sectional view through the actuator and a connecting plug receptacle therefor.

Figure 3 is a plan view of a baffle element of the actuator, while Figures 4 and 5 are respectively a bottom and a top end view of the actuator.

Figure 6 is an elevational view of the actuator.

Referring now to the drawings, and more particularly to Figure 1, 1 indicates an electric actuating circuit shown in part, and including a source of electric current at 2. At 3, the actuator of the invention is shown diagrammatically as being connected in the circuit 1.

Referring to Figure 2 wherein the actuator is illustrated in detail, 4 indicates a cylindrical housing of the actuator formed with a cylindrical chamber 5, the inner surface of which is covered by a metallic electrode 6. A metallic

ring 7 is disposed in the upper part of chamber 5, in intimate contact with electrode 6. A terminal wire 8 is connected to the ring 7 and is carried through a passage 9 in a partition 10 formed within the housing 4. The wire 8 terminates in a recess 11 of the housing where it is connected to a terminal prong 12 mounted in a connector receptacle 13.

The partition 10 has an aperture 14 into which is cemented a suitably shaped boss portion 15 of a cylindrical member 16. The outer surface of member 16 is covered by a metallic electrode 17. An electro-conductive ring 18 is fastened about a constricted portion 19 of the member 16 and serves as a conducting intermediary between the electrode 17 and a terminal wire 20 secured to the inside of the ring 18 and terminating in the recess 11 where it is connected to a terminal prong similar to that of wire 8. A groove 21 is provided in portions 19 and 15 to accommodate the wire 20. The receptacle 13, by means of a coupling 22, is connected to a socket 23 which forms the terminal for circuit wires 24 and 25. The receptacle 13 and the socket 23 are not shown in detail as they form no part of the invention and are of a standard type.

The cylindrical member 16 has a centrally located bore or recess 26 for receiving a stud-like central projection 29 of a fluid admission member 28 attached to one end of the housing 4. A bayonet type lock 27, comprising a pin 30 and a corresponding groove 31 in the projection 29 and the member 16 respectively, is provided to retain the member 28 with respect to the housing 4. A spring 32, disposed in the recess 26, bears against the top of the projection 29 and serves to yieldingly maintain the fluid admission member 28 in its locked position.

The recess 26 in member 16 has an extension 33 of smaller diameter, into which is secured by means of a pin 34, a spring carrying member 35, formed with an enlargement 36 to enable it to support the spring 32, which has its diameter reduced for cooperation therewith at either end as indicated at 37.

The member 28 is essentially in the form of a cap or closure which fits over a reduced end portion 38 of the housing 4, and is provided with water inlet apertures 39 as shown in Figure 4. Water may enter the chamber 5 only past baffles 40 and 41, the shape of which is shown in Figure 3, and which are arranged to present a so-called "staggered" obstacle to any entering fluid. These baffles are mounted on the projection 29, and

are separated by a bushing 42 and held in place by a collar 43.

As indicated in Figures 5 and 6, the receptacle 13, which forms a closure for the recess 11, is held onto the housing 4 by means of screws 44. The recess 11, although not indicated, may be filled partly or wholly, if desired, with an insulating compound before the receptacle is assembled to the housing so as to eliminate the possibility of any short-circuit between wires 8 and 20.

Figure 6 illustrates surface cavities 45 provided on the housing for frictional cooperation with holding means such as a bracket, or the like.

The upper portion of the chamber 5 is vented to the atmosphere through apertures or passages 46 in the wall of the housing 4. The number of these vents, of which four are shown, may be varied in accordance with their need.

In operation, the actuator, which may be mounted on the aircraft in any position and in whatever numbers desired, is prevented from closing the circuit in which it is connected unless actually immersed in water, by the presence of baffles 40 and 41 which, due to their "staggered" arrangement, impede the ingress of rain or spray but do not stop the entrance of water when actual immersion occurs. As water enters the chamber 5, the air entrapped therein is vented through the apertures or openings 46, and an electro-conductive path is established between the electrodes 6 and 17 with the resultant actuation of the circuit represented by conductors 24 and 25. The arrangement and type of the electrode surfaces insure small current densities and a relatively large current to be caused to flow, while any gas developed in chamber 5 due to electrolytic action is vented through the apertures 46. The distance between the surfaces of the electrodes 6 and 17 is dimensioned so as to minimize the possibility of any short-circuit due to accumulation of foreign matter, such as salt, frequently encountered on marine craft. Easy accessibility of these electrodes for testing purposes is also attained because of the simplicity of removing closure member 28, which only requires a lengthwise thrust against the force of the spring 32 and a sidewise twist to release it from its locked position.

The conducting surfaces of the electrodes 6 and 17 may be separate metallic cylinders secured to the inside of the housing 4 and over member 16, but in the preferred embodiment, in order to eliminate manufacturing and assembly difficulties encountered in the case of metallic cylinders, these surfaces may be provided by first metallizing and then plating them. Any possibility of foreign matter lodging between the conducting surfaces and their backing, as well as the necessity for cleaning connected therewith is thus eliminated.

The housing 4, and members 16 and 28 are made of a non-conductive material which preferably lends itself to simple manufacture by die-forming methods, as is the case with a great number of well known plastics, of which perhaps, that known as Bakelite, is the most readily suggestible.

To remove the entire actuator assembly, only the loosening of the coupling 22 is required, whereupon the device may be pulled from the socket 23.

From the foregoing description, it will be seen, that the present invention provides an electric

circuit immersion actuator, which is reliably effective immediately upon immersion, the electrodes having sufficient current carrying capacity even for partial submersion.

It will be seen further that my invention accomplishes the various objects and advantages pointed out herein. Finally, while my invention has been illustrated and described with specific reference to the accompanying drawings, it will be apparent to those skilled in the art that the invention resides in certain principles of construction which may be embodied in various other forms without departing in any manner from the spirit and scope of the invention, and I, therefore, do not wish to be limited to the specific disclosure, but rather to the scope of the appended claims.

I claim:

1. An immersion actuator for an electrical circuit comprising housing means having a chamber therein and having an opening at one end thereof, electrodes in said chamber and secured to said housing means, closure means for said opening having fluid inlet means, and means associated with said housing means and said closure means for removably securing said closure means to said housing means.

2. An immersion actuator for an electrical circuit comprising a substantially tubular housing member having a chamber therein and having a venting aperture extending from said chamber, said member having an opening at one end thereof, electrodes in said chamber and secured to said housing member, a closure member for said opening having a fluid inlet aperture, and means associated with said closure member and said housing member for removably securing said closure member to said housing member.

3. An immersion actuator for an electrical circuit comprising housing means having a chamber therein and having an opening at one end thereof, electrodes in said chamber and secured to said housing means, closure means for said opening having fluid inlet means, baffle means on said closure means adjacent said fluid inlet means, and means associated with said housing means and said closure means for removably securing said closure means to said housing means.

4. An immersion actuator for an electrical circuit comprising a substantially tubular housing member having a chamber therein and having an opening at one end thereof, electrodes in said chamber and secured to said housing member, a closure member for said opening having a fluid inlet aperture, baffle in said closure member adjacent said fluid inlet aperture, and means associated with said closure member and said housing member for removably securing said closure member to said housing member.

5. An immersion actuator for an electrical circuit comprising housing means having a chamber therein and having an opening at one end thereof, electrodes in said chamber and secured to said housing means, closure means for said opening having fluid inlet means, means associated with said housing means and said closure means for removably securing said closure means to said housing means, and resilient means for maintaining said securing means in engagement to prevent accidental removal of said closure means.

6. An immersion actuator for an electrical circuit comprising a substantially tubular housing member having a chamber therein and having an opening at one end thereof, electrodes

in said chamber and secured to said housing member, a closure member for said opening having a fluid inlet aperture, means associated with said closure member and said housing member for removably securing said closure member to said housing member, and a spring urging said securing means into engagement to prevent accidental removal of said closure member.

7. An immersion actuator for an electrical circuit comprising a substantially tubular housing member having a chamber therein and having an opening at one end thereof, electrodes mounted in said chamber and secured to said housing member, a closure member for said opening having a fluid inlet aperture and having a chamber formed therein, baffles in the chamber of said closure member disposed adjacent said fluid inlet aperture, and means associated with said closure member and said housing member for removably securing said closure member to said housing member.

8. An immersion actuator for an electrical circuit comprising a substantially tubular housing member having a chamber therein and having an opening at one end thereof, electrodes mounted in said chamber and secured to said housing member, a closure member for said opening having a fluid inlet aperture, one of said members having a projection structurally associated therewith and the other of said members having a bayonet groove structurally associated therewith to provide a bayonet joint for removably securing said closure member to said housing member, and a spring for retaining said projection in said groove to prevent accidental removal of said closure member.

9. An immersion actuator for an electrical circuit comprising housing means having a fluid receiving chamber therein and having an opening at one end thereof, electrodes in said chamber, secured to said housing means and terminating within said chamber adjacent said open

end thereof, closure means for said opening having fluid inlet means, and means associated with said housing means and said closure means for removably securing said closure means to said housing means.

10. An immersion actuator for an electrical circuit comprising substantially tubular housing means having a chamber therein open at one end thereof, said housing means having a longitudinal bore therein adjacent said open end of said chamber, electrodes mounted in said chamber and secured to said housing means, closure for said open end of said chamber having fluid inlet means, means associated with said housing means and said closure means for removably securing said closure means to said housing means, and a spring in said bore for maintaining said securing means in engagement to prevent accidental separation of said closure means from said housing means.

11. An immersion actuator for an electrical circuit comprising substantially tubular housing means having a fluid receiving chamber open at one end and provided with an aperture adjacent the other end, said housing means having a longitudinal bore adjacent said open end of said chamber; electrodes mounted in said housing means, secured to said housing, and terminating within said chamber adjacent said open end thereof; closure means for said open end of said chamber having fluid inlet means and a chamber; baffle members secured in the chamber of said closure means and disposed adjacent said fluid inlet means; means associated with said housing means and said closure means for removably securing said closure means to said housing means; and a spring in said bore and engaging said closure means for maintaining said securing means in engagement to prevent accidental separation of said closure means from said housing means.
